UNITED STATES PATENT OFFICE

ELIZABETH W. JANKE AND ALFRED H. JANKE, OF PLAINFIELD, NEW JERSEY; SAID
ALFRED H. JANKE ASSIGNEE TO SAID ELIZABETH W. JANKE

MULTIPLE-UNIT PLATE RACK

Application filed September 14, 1929. Serial No. 392,504.

Our invention relates to holders for individual plates carrying food ready for serving, the holders being shaped so that they can be readily superposed upon each other in considerable number, thereby conserving space on the shelf or support upon which the rack rests. Our novel plate rack is of particular advantage for storing foods assembled on plates ready for serving, such as salads or desserts, in refrigerators which have a limited amount of shelf space and in which usually the vertical space between two shelves cannot be sufficiently utilized, because plates containing ready prepared food cannot very well ordinarily be placed on top of each other. By providing a multiple unit rack according to our invention, in which individual units can easily be taken away from or added to the rack, the size of the rack can thus be adapted to the vertical space between the refrigerator shelves. The rack can also be divided into several racks of suitable height, thus utilizing the refrigerator space to the fullest extent.

Several modifications of the manner in which our invention may be reduced to practice are illustrated in the accompanying drawings in which

Fig. 1 represents in perspective view a rack unit made of wire,

Fig. 2 represents the triangular wire element which holds the central wire spider in Fig. 1, together at its arm ends,

Fig. 3 shows in central vertical section on the line 3, 3 in Fig. 1 the details of the construction of the foot and socket at each arm end, and shows how the foot of the superposed unit engages a socket of the unit below,

Fig. 4 represents an individual wire length having one of its ends bent into a foot, and the other end bent into a socket, three of such lengths forming the three-armed spider shown in Fig. 1,

Fig. 5 represents a modified form of a unit showing how such a unit can be made of a plurality of lengths of flat material,

Fig. 6 represents a side elevation of one corner of two superposed units, some of the parts being broken away, and

Fig. 7 shows one of the corners of the unit in Fig. 5 in horizontal section on the line 7, 7 in Fig. 5.

Referring more particularly now to Figs. 1 to 4, the triangular spider 1 is composed of three wires 2, each bent in the form shown in Fig. 4, one end of each wire being bent at right angles and twisted to form a foot 3, and the other end being bent at right angles in the opposite direction and being coiled to form a socket 4. Three of such blanks are assembled at their central portions *a*, so that the two straight portions of each blank are paired with the corresponding straight portions of the adjacent blanks in such manner that the foot 3 at the end of one blank is joined with the socket 4 of the adjacent blank, whereupon the two wires thus paired are twisted together to form the arms of the spider. In order to retain the arms in their angular relation to each other, they are connected by a triangular wire element 5 shown in detail in Fig. 2, preferably in such manner that the corners of the wire element 5 are crimped around the arm ends, thereby clamping together the two wires which form the foot and the socket at the arm end.

In order to raise the supporting point of the foot within the socket of the adjacent unit for reasons of frame rigidity to be explained later, and also to maintain the spacing between two adjacent units, indicated in Fig. 3 by the arrow *b*, the end of the wire which forms the foot 3 is extended partway into its pertaining socket, where the wire end is bent over as shown at 7, the foot 3 of the superposed unit resting upon this bent portion 7. At the same time the extension of this hook shaped foot wire into the socket 4 affords facilities for more securely joining the foot to its pertaining socket, such as by soldering the crimped corner of the wire 5 together with the wires of the foot 3, and the wire forming the socket coil 4 at the arm end, whereby the solder can be easily made to flow partway into the socket 4 as shown in Fig. 3 in stippled form. Fig. 1 shows in dot-dash lines a unit superposed upon the unit shown in full lines. Inasmuch as the frame is composed of rather thin wire elements, and since

it extends substantially only in one plane, such a unit alone by itself would form a rather weak support for a plate. When several units are assembled however, their interengaging feet and sockets counteract the downward bending of the frame under the load in such manner, that the wire elements of the horizontal frame portion become subject substantially only to tension stresses and are prevented from sagging under the load. These favorable stress conditions exist because when the frame arms of a separate unit sag under the load, its feet swing outward and its oppositely directed sockets inward. When several units are interengaged with their feet and sockets, the foot of one unit swings opposite to the direction in which the socket of the other unit swings in which that foot is seated, and thus the two forces neutralize each other, and in effect the horizontal frame elements virtually become bars fixed at both ends. For this reason it is of advantage to have the foot end of one unit seated rather in the upper portion of the socket of the adjacent unit (as shown in Fig. 3) than in the bottom of the socket.

Referring to Figs. 5 to 7, these figures show how such a skeletonized unit may be made of flat lengths of material such as sheet stock. For convenience, we have again shown a triangular skeletonized frame, though any other form may be used. As will be noted from Fig. 5, the three arms of the spider are composed of straight lengths 10 of thin strips of material which for purposes of rigidity are provided with longitudinal ribs 11. The three strips are joined together, for instance by a rivet 12, at their inner ends, their outer ends being bent downward to form the feet 13 of the unit, each foot being besides bent on its central longitudinal axis to form a channel element by which rigidity is imparted to the foot. At the point where arm 10 is bent to form the foot, and which is indicated in Fig. 6 by *c*, the material is crimped so as to accommodate the surplus material accruing when the channel of the foot is formed and the arm bent at right angles. This crimping imparts rigidity to the corner so that the foot will remain substantially at right angles to the horizontal portion of each arm.

The outer ends of the three arms 10 are tied together by tie strips 14 which for purposes of rigidity may also be provided with longitudinal ribs 15, the tie strips and the arms being joined by any suitable means, for instance by rivets 16. The ends of each tie strip 14 are bent upward so that when the ends of the tie strips are joined together as shown in Fig. 7, they form a channel 17, the tie pieces being slightly longer than the distance between two feet 13, so that the channel element can serve as a socket for the channeled foot 13 of the superposed unit. In order to provide stops for the superposed feet,

each socket 17 may be provided with a plate 18 which may at the same time serve the purpose of tying together the constituent portions of the socket 17. Also in this case a considerable rigidity is imparted to the structure by the relative arrangement of the sockets and feet, in so far as also in this modification, when the load on the unit tends to deflect the center downward, and thus deflects its feet outward, the unit below through its socket portions will counteract this outward bending of the feet, because the load on the lower unit will tend to bend the socket portions of that unit inwardly. The sockets and feet, being short and rigid by virtue of so their structure, as compared with the free lengths of material, used in the frame, these bending stresses are easily absorbed by the feet and sockets without deformation. Owing to the existence of substantially only tension stresses in the frame, also comparatively soft materials, such as aluminum may be used in manufacturing the units.

We claim:

1. A vertical multiple unit plate rack built up of a plurality of superposed independent units, each unit adapted to support a plate and constituting a skeletonized polygonal frame, composed of a plurality of lengths of wire, twisted together in pairs and shaped at each polygon corner, so that one wire forms a foot and the other wire a socket for supportingly engaging respectively the socket and foot at the corresponding corners of the adjacent units to hold the units in spaced relation to each other.

2. A vertical multiple unit plate rack built up of a plurality of superposed independent units, each unit adapted to support a plate and constituting a three armed spider, composed of a plurality of wires twisted in pairs to form the spider arms, one wire at each arm end being bent to form a foot and the other wire being shaped to form a socket for supportingly engaging respectively the socket and foot at the corresponding arm ends of the adjacent units to hold the units in spaced relation to each other.

3. A vertical multiple unit plate rack built up of a plurality of superposed independent units, each unit adapted to support a plate and constituting a three armed spider, composed of a plurality of wires twisted in pairs to form the spider arms, one wire at each arm end being bent to form a foot and the other wire being coiled to form a socket for supportingly engaging respectively the socket and foot at the corresponding arm ends of the adjacent units to hold the units in spaced relation to each other, and a triangular wire element joined to and connecting the arm ends of said spider.

4. A vertical multiple unit plate rack built up of a plurality of superposed independent units, each unit adapted to support a plate

and constituting a three armed spider composed of three lengths of wire joined near their middle portions and having their free lengths twisted together in pairs to form the spider arms, the two wires of each pair being shaped at their ends to form a foot and a socket for supportingly engaging respectively the socket and the foot at the corresponding arms of the adjacent units, and a triangular wire element tying the arm ends of the spider together and being clamped at its corners around the pertaining arm end between the foot and the socket.

5 5. A vertical multiple unit plate rack built up of a plurality of superposed independent units, each unit adapted to support a plate and constituting a skeletonized frame, extending substantially in one plane only and having at least three points of support at its 10 periphery, and having feet and sockets at said supporting points, extending in opposite directions at right angles to said plane, and being adapted to respectively engage the sockets and feet of the adjacent units to maintain the frames in spaced relation to each other, and whereby said units mutually reinforce each other's carrying surfaces under load.

6 6. A vertical multiple unit plate rack built up of a plurality of superposed independent units, each unit adapted to support a plate and constituting a skeletonized frame, extending substantially in one plane only and having at least three points of support at its 15 periphery, and having feet and sockets at said supporting points, extending in opposite directions at right angles to said plane, and being adapted to respectively engage the sockets and feet of the adjacent units to maintain the frames in spaced relation to each other, the stresses upon each frame due to the load being counteracted by the interengagement of the feet and sockets of the assembled units, so that the frame elements 20 are subject substantially only to tension stresses.

7 7. A vertical multiple unit plate rack built up of a plurality of superposed independent units, each unit adapted to support a plate and constituting a skeletonized frame, extending substantially in one plane only and having at least three points of support at its periphery, and having feet and sockets at said supporting points integral 25 with the frame structure and extending in opposite directions at right angles to said plane, and being adapted to respectively engage the sockets and feet of the adjacent units to maintain the frames in spaced relation to each other, the stresses upon each frame due to the load being counteracted by the interengagement of the feet and sockets of the assembled units, so that the frame elements 30 are subject substantially only to tension stresses.

8. A vertical multiple unit plate rack built up of a plurality of superposed independent units, each unit adapted to support a plate and constituting a skeletonized frame, composed of a plurality of lengths of material joined together and extending substantially in one plane only, said frame having at least three points of support at its periphery at some of the junction points of said lengths, and having feet and sockets at said supporting points formed by said lengths and extending in opposite directions at right angles to said plane and being adapted to respectively engage the sockets and feet of the adjacent units to maintain the frames in spaced relation to each other, the stresses upon each frame due to the load being counteracted by the interengagement of the feet and sockets of the assembled units, so that the frame elements are subject substantially only to tension stresses.
